CLAIM

The ornamental design for a set of booties for dogs as shown and described.

DESCRIPTION

FIG. 1 is a front perspective view of the front boot of a set of booties for dogs, with a hook and loop surface fastener strap fastened, showing my new design;

FIG. 2 is a right side view thereof;

FIG. 3 is a left side view thereof;

FIG. 4 is a front view thereof;

FIG. 5 is a back view thereof;

FIG. 6 is a top view thereof;

FIG. 7 is a bottom view thereof;

FIG. 8 is a back view of the front boot of the set of booties for dogs of FIG. 1, shown in a second configuration with the hook and loop surface fastener strap unfastened;

FIG. 9 is a front perspective view of the rear boot of the set of booties for dogs with a hook and loop surface fastener strap fastened, showing my new design;

FIG. 10 is a right side view thereof;

FIG. 11 is a left side view thereof;

FIG. 12 is a front view thereof;

FIG. 13 is a back view thereof;

FIG. 14 is a top view thereof;

FIG. 15 is a bottom view thereof; and,

FIG. 16 is a back view of the rear boot of the set of booties for dogs of FIG. 1, shown in a second configuration with a hook and loop surface fastener strap unfastened.

The broken lines in the drawings illustrate portions of the set of booties for dogs that form no part of the claimed design.
